UNITED STATES PATENT OFFICE

147,648

DESIGN FOR A RADIO CABINET

Carl Gallo, Riverdale, N. Y., assignor to Empire Designing Corporation, New York, N. Y., a corporation of New York

Application February 20, 1946, Serial No. 126,745

Term of patent 14 years

(Cl. D56—4)

To all whom it may concern:

Be it known that I, Carl Gallo, a citizen of the United States, and residing in Riverdale, in the county of New York and State of New York, have invented a new, original, and ornamental Design for a Radio Cabinet, of which the following is a specification, reference being had to the accompanying drawings, forming a part thereof.

Fig. 1 is a top plan view of a radio cabinet showing my new design;

Fig. 2 is a front elevational view; and

Fig. 3 is a side elevational view thereof.

The rear of the radio cabinet is similar to the front except for the omission of the tuning con-

trols and the window box simulating grille element shown in Fig. 2.

I claim:

The ornamental design for a radio cabinet, as shown and described.

CARL GALLO.
